Fig. 1.

Fig. 2.

A technical drawing showing a cross-section of a cylindrical component. The base of the cylinder features a series of vertical, flared ribs. The number '17' is positioned above the top of the cylinder, and the number '16' is positioned below the base, near the ribs.

A diagram of a cylindrical container. The bottom portion of the cylinder is shaded with diagonal lines, while the top portion is white. A vertical line labeled '13' is drawn on the right side of the cylinder.

A diagram of a U-shaped tube. The left side shows a horizontal tube segment with a vertical leg extending upwards from its center. The right side shows a horizontal tube segment with a vertical leg extending downwards from its center. The label '34' is positioned to the right of the tube's junction point.

6

A circular metal gasket with a central hole and a raised outer edge. It is marked with the number 17 on its right side and 5-1 on its top left side.

39 13 7

A detailed technical drawing of a gas cylinder assembly. It features a vertical cylinder body with a horizontal valve assembly attached to its top. The valve assembly includes a handle, a seat, and a stem. A pressure gauge is mounted on the side of the cylinder body. The drawing uses lines and arrows to indicate specific components and their locations.

ATTORNEY.

UNITED STATES PATENT OFFICE

MAURICE MILLER, OF POTTSTOWN, PENNSYLVANIA

METHOD OF AND APPARATUS FOR BLOCKING HATS

Application filed July 11, 1928. Serial No. 291,793.

The object of this invention is to devise a novel and simplified method of and apparatus for blocking hats which can be economically manufactured and which will enable the operator to refinish a hat so that it will be in substantially the same condition as a new hat.

This invention relates more particularly to the manner of blocking the crown and the brim.

With the above and other objects in view, as will hereinafter more clearly appear, my invention comprehends a novel method of and apparatus for blocking hats.

It further comprehends a novel method of blocking the hat brims wherein the brim is subjected to the action of the steam during the blocking and shaping operation, and at the same time the leather sweat band is protected and insulated from the action of the steam.

My invention further comprehends a novel hat blocking machine wherein novel means are employed for treating the crown and novel means for treating the brim of the hat.

Other novel features of construction and advantage will hereinafter more clearly appear in the detailed description and the appended claims.

For the purpose of illustrating the invention, I have shown in the accompanying drawings, a typical embodiment of it, which, in practice, will give satisfactory and reliable results. It is, however, to be understood that the various instrumentalities of which my invention consists can be variously arranged and organized, and my invention is not limited to the exact arrangement and organization of these instrumentalities as herein set forth.

Figure 1 is a perspective view of a hat blocking machine embodying my invention and by means of which my novel method may be carried out.

Figure 2 is a sectional view of the crown kettle.

Figure 3 is a sectional view of the brim treating mechanism.

Similar numerals of reference indicate corresponding parts.

Referring to the drawings:

1 designates supporting standards having cross members 2 which support a bottom shelf 3. 4 designates a table which is secured to the standards 1 in any desired or conventional manner. The table 4 has rising from it the posts 5 which support the shelves 6 and 7 which are adapted to receive the blocks 8. The upper shelf 7 is preferably provided with a back plate 9 on which can be indicated the name of the machine or any other desired advertising data.

10 designates a steam line which leads from a source of steam supply and which is provided with a control valve 11. The main steam pipe 10 is provided with a branch pipe 12 which extends up through the table top 4 and communicates with the interior of a crown kettle 13. This crown kettle, as seen in Figure 2, has a baffle 14 so that the steam will not impinge directly against the crown of the hat 15 which is mounted on the block 16. The upper edge of the crown kettle 13 carries a wooden rim 17 which supports the hat 15 and the block 16 contained within the hat.

The branch pipe 12 is controlled by means of a valve 18 which is connected by means of a link 19 with a rod 20 which latter, at its lower end, is secured to a foot treadle 21, pivotally supported at 22 on the shelf 3. The main steam pipe 10 leads by pipe 23 to the brim treating member 24 and extends through the table 4 so as to support the brim steaming member. The steam line 10 is provided with a valve 25 which controls the passage of steam to the brim treating member 24. A link 26 has one end connected with the valve 25 and its opposite end is connected with a rod 27 which is connected to a foot treadle 28 pivotally supported at 29 on the shelf 3.

The brim treating member 24 is in the form of a casing having an internal chamber 30 and having its central portion downwardly curved as at 31 and its top face is substantially flat as at 32 and is provided with a desired number of steam ports 33.

The purpose of the downwardly curved position 31 is to prevent the sweat band of the hat being subjected to the action of the

steam and heat. If the sweat band is subjected to the action of steam it will be dried out and shrivel up, and it would be necessary to replace the sweat band with a new one.

5 In practice, I preferably employ a drainage conduit 34 which communicates with the bottom of the chamber 30 of the brim treating member 24 and with the lower end of the chamber of the crown kettle 13 in order 10 to permit the water of condensation to drain away. This drainage conduit 34 may lead to any desired point of discharge.

In the operation and in the carrying out 15 of my novel method, the hat is first dry cleaned or cleaned by any other desired or conventional method. The hat is then placed on a wooden block 16 of the proper size and with the block, is placed up-side down in the crown kettle 13. The operator then presses 20 downwardly the foot treadle 21 to open the valve 19 and permit the steam to pass through the steam pipe 10 into the crown kettle 13. As the steam enters this kettle, it strikes the baffle 14 and is directed outwardly 25 so that the hat is not subjected to the direct pressure of the steam.

The steam is left on for a desired interval 30 until the crown of the hat has been subjected for the necessary period to the action of the steam. The hat with the block within it is then taken from the crown kettle and the crown is brushed and moulded while hot until it fits the block. This can be done by 35 means of the hand or by the use of a lure of any desired character, such as for example, the tollickers, which are usually employed.

The hat is then stripped from the block 40 16 and placed on the brim treating member 24 and the treadle 28 is depressed to open the valve 25 and permit the steam to pass into the chamber 30 of the steam kettle. The brim is brushed and moulded to shape with wooden tools while in a heated condition due 45 to the action of the steam, and it is then removed from the brim treating member and allowed to cool.

In accordance with this invention the hat 50 can be accurately moulded to the desired shape so that it will be in substantially the same condition as when it was first manufactured.

During the treatment of the brim with 55 steam, the steam can not enter the chamber of the hat since the depressed face 31 is imperforate and is a sufficient distance from the head receiving opening of the hat to prevent the sweat band from being affected by the steam which is being used to treat the brim.

60 In so far as I am aware, I am the first in the art to provide a brim steam table for the treatment of the brim of the hat in which the sweat band is insulated or protected from the action of the steam passing to the brim.

65 It will now be apparent that I have devised

a new and useful method of and apparatus for blocking hats which embodies the features of advantage enumerated as desirable in the statement of the invention and the above description, and while I have, in the present instance, shown and described a preferred embodiment thereof which will give in practice satisfactory and reliable results, it is to be understood that this embodiment is susceptible of modification in various particulars without departing from the spirit or scope of the invention or sacrificing any of its advantages.

Having thus described my invention what I claim as new and desire to secure by Letters Patent, is:—

1. In a hat blocking machine, a table, shelves carried thereby, a brim treating member above said table comprising a chambered casing having the central portion of its top face imperforate and the portions surrounding said imperforate portion apertured, and means under the control of the operator to pass steam to the chamber of said casing.

2. In a hat blocking machine, a brim treating member comprising a casing having an internal chamber, the outer face of which is inwardly deflected and imperforate at its central portion and apertured at the portions surrounding said central portion.

MAURICE MILLER.
